UNITED STATES PATENT OFFICE.

ROBERT A. BROOKS, OF CHICAGO, ILLINOIS.

FLUSHOMETER.

No. 834,256.

Specification of Letters Patent.

Patented Oct. 30, 1906.

Application filed November 2, 1904. Serial No. 231,059.

To all whom it may concern:

Be it known that I, ROBERT A. BROOKS, a citizen of the United States, and a resident of the city of Chicago, in the county of Cook and State of Illinois, have invented certain new and useful Improvements in Flushometers; and I do hereby declare that the following is a full, clear, and exact description of the same, reference being had to the accompanying drawings, and to the letters of reference marked thereon; which form a part of this specification.

This invention relates to flushometers, and more particularly to an automatically-operating flushometer or flush-valve of that class embodied in my application for patent entitled "Flushometer," filed December 4, 1903, Serial No. 183,790.

Heretofore urinals have sometimes been flushed from tanks in which a float-valve acts at regular intervals to open the discharge. In such devices, however, a large quantity of water is usually delivered at each flushing, and it is difficult to regulate the amount and the frequency of the discharge. The tanks are also unsightly in appearance and have proven objectionable because requiring constant repairs.

The object of this invention is to afford a self-operating flushometer or flush-valve of small size and adapted to be connected in the supply-pipe leading to urinals and other toilet-fixtures and by means of which the quantity of fluid delivered in flushing and the duration of the flush can be perfectly regulated and also adapted to be adjusted for flushing at either short or long intervals, as preferred.

The invention consists in the matters hereinafter described and more fully pointed out and defined in the appended claims.

In the drawings, Figure 1 is a central vertical section showing the flush-valve closed. Fig. 2 is a section taken on line 2 2 of Fig. 1. Fig. 3 is a section taken on line 3 3 of Fig. 1. Fig. 4 is a view similar to Fig. 1, but showing the flushometer immediately after the full opening of the valve. Fig. 5 is a section taken on line 5 5 of Fig. 4. Fig. 6 is a section taken on line 6 6 of Fig. 4.

As shown in said drawings, said flushometer or flush-valve comprises a hollow base A, of cast metal, in which the flush-pipe A' communicates at its axis and leads to the fixture to be flushed. A pipe a connects in the side of said base and communicates with the inter-

rior cored chamber therein. Threaded and brazed upon the upper end of said base is a tubular casing a', which may be of any desired diameter and within which is contained the operating mechanism. The upper end of said casing is internally screw-threaded and, as shown, is closed by a removable screw cap or cover a''. Threaded into the top of said base and extending downwardly in the chamber therein is a cylindric sleeve B, the upper end of which is flared outwardly, as shown in Figs. 1 and 2, which extends upwardly for approximately a third of the height of the casing and in which fits a counterweight B', of lead or other suitable material, on the lower end of which is provided a hydraulic washer of leather b', which fits within the sleeve B and is held in place by a disk or plate b'', rigidly secured beneath the counterweight by means of a pipe or sleeve b'', which extends axially through said counterweight and is threaded at its lower end for engagement with said valve disk or plate b''. Within said sleeve or tube b'' is provided a stem b'', having an enlarged head b'' at its upper end and a sliding washer b'' near its lower end. A spiral pushing-spring b'' is engaged around said stem between the head of the same and said washer. Beneath said washer and engaging against the valve-plate b'' is a stronger spring b''. Said springs act together to hold said stem in an elevated position, and on the lower threaded end of said stem, which extends through the valve-plate b'', is carried the flushing-valve plate B'', affording a downwardly-opening recess, in which is secured a fiber or other suitable washer b'', which affords a closure for the flush-pipe. As shown, a reversible valve-seat is provided between the flush-valve and the flush-pipe, comprising a sleeve b'', one end of which extends into the flush-pipe and the other of which affords a seat for the fiber washer b''. A central peripheral flange b'' is provided on said sleeve, and in each side of the same in close relation to the sleeve is a concentric channel or groove. A leather or other suitable packing-washer b'' is engaged on the lower end of said sleeve and bears against the seat in the bottom of the base, as shown in Figs. 1 and 4, and affords a tight joint. The upper end of said pipe or sleeve b'' is externally screw-threaded and closed and extends above said weight, and an oil or fluid containing chamber C is carried thereon,

comprising a base portion provided with a threaded axial socket to receive the upper end of said pipe b^3 and cylindric sides c' , which extend upwardly therefrom and are flared outwardly at the top, as shown at c^2 , into close proximity with the inner side of the casing. Said oil chamber or cup is of a height approximately equal to the height of the sleeve B and with its contents afford a part of the weight whereby the valve is closed. Threaded into the top of said casing is an externally-threaded ring d , having integral radial and downwardly-inclined arms d' , which are united by a central hub d^2 , positioned axially of the casing. Fitting loosely in and extending downwardly from said hub is a tubular stem D, near the upper end of which is a flange d^4 , which bears against the under side of said hub. The upper end of said stem is provided above the hub with an internally-threaded seat adapted to receive the threaded end of the tubular adjusting-nut d^5 , provided at its upper end with a flange d^6 , which extends peripherally beyond the stem and is adapted for manual engagement. Said tubular stem D is screw-threaded at its lower end, and supported thereon at a point slightly below the top of the oil-chamber when the flushometer is fully closed is a piston-head D', provided on its upper side with a peripheral and an upwardly-directed flange d^7 , which fits closely within said chamber. On the under side of said piston-head is provided a hydraulic packing-washer d^8 , which is held in place by a downwardly-flanged plate d^9 , which fits within said washer and is also threaded on the lower end of said stem, which extends through and below the same. Said stem at its lower end is reamed out to afford a cylindric chamber, which tapers upwardly and communicates, through a restricted passage, with the bore in the stem, and a valve-closure d^{10} is secured loosely therein and is tapered at its upper end to fit the taper in said chamber. Said valve-closure is retained from falling from said valve-chamber by means of a nut d^{11} , which is threaded on the lower end of the stem and provided with a restricted aperture therethrough sufficiently small to prevent said closure from falling therethrough, and, as shown, the lower end of said closure is notched transversely to prevent the same closing said aperture, thus affording a passage through the lower end of said stem by means of which a liquid contained within the cup above the piston-head and entering the stem through the aperture d^{12} slightly above said piston-head is permitted to escape downwardly into the oil-chamber and through which, if the closure d^{10} is held from seating, the fluid in the chamber can also pass upwardly, escaping through said aperture above the piston as the flushing-valve is opening. For this purpose a threaded rod d^{13} extends

through said nut d^5 and the stem D and is adapted to be engaged at its lower end with a needle d^{14} , carried on the end of said closure d^{10} , which holds the same from seating. A milled head d^{14} is provided on the upper end of said rod d^{13} , whereby the same is actuated, and, as shown, a set-nut d^{15} is engaged on said rod and is adapted to rigidly engage the same in adjusted position. As shown, a downwardly-opening valve is provided through said piston-head, adapted to afford quick release of the pressure on the fluid in the cup and a comparatively rapid flow of the fluid from above the piston through said valve back into said cup or oil-chamber. For this purpose, as shown, an aperture is provided through said piston-head adjacent its periphery and a tube E is threaded therein and extends above said head and is provided with a plurality of apertures therein, as shown in Figs. 1 and 4. The lower end of said tube is reamed out to afford a conical seat adapted to receive a conical closure E', on the upper end of which is an upwardly-extending stem e. Pivoted supported on the under side of the head, on a downwardly-extending bracket e', is a lever e^2 , upon the lighter end of which is pivotally engaged said closure in position to seat in the lower end of said pipe. The other end of the lever is heavier and directed downwardly into position to be engaged and actuated by the bottom of the oil-chamber at approximately the upward limit of movement thereof.

As shown, the upper end of the pipe E is screw-threaded and secured thereon in an internally-threaded closed cap e', which is shaped at the upper end to adapt the same for engagement with a screw-driver, wrench, or other suitable tool for turning the same, and at the lower end of which is afforded a larger bore e^5 , into which the apertures in said pipe open and within which seats the upper end of a spiral spring e", the lower end of which bears upon the piston-head and acts to hold said cap in adjusted position when turned upwardly or downwardly on said stem to partly close one or more of the apertures extending therethrough.

The operation is as follows: In adjusting the device for use the base A is screwed upon the flush-pipe A' and connected with a supply-pipe a, as shown in Figs. 1 and 4. The weight B' and the attached oil or fluid containing chamber C thereon are dropped into place, with the flush-valve thereof closing the upper end of the flushing-pipe. Sufficient oil or other suitable fluid is then poured into the oil cup or chamber to nearly fill the same, and the ring d, with the piston-head swiveled therein, is inserted in the top of the cup and is screwed downwardly therein, bringing the top of said piston below the top of the oil cup or chamber when the cup is at its lowest po-

sition, as shown in Fig. 1. The rod d^{13} is then adjusted to prevent the closure d^{10} from seating upwardly in the stem and the water is turned on to enable the device to be timed. 5 Should the flushing occur too rapidly, the threaded rod d^{13} is retracted slightly to permit the closure d^{10} to more nearly seat in said stem. This retards the flow of the fluid above the piston through the valve in the 10 stem, thus enabling the valve to be accurately timed for opening, inasmuch as the flushing-valve cannot open until the greater part of the fluid in the chamber has passed above the piston. Having timed the device 15 satisfactorily for the intervals between successive flushings, the duration of the flush and necessarily the amount of water or other fluid delivered during flushing is regulated by adjusting the screw-cap e^4 . If the screw-cap is elevated sufficiently to expose all the 20 apertures leading into the pipe E to their full extent, the oil or other fluid will quickly flow back into the oil-chamber, permitting the same to descend quickly by its own gravity and that of the weight B' , closing the 25 valve, affording a very brief flush. If a long flush is desired, the screw-cap is turned downwardly, partly obstructing said apertures and limiting the flow of the fluid from 30 above the piston through the same. In this manner the discharge may be varied to a long or short period, as preferred. Having adjusted the device, as before described, and the valve being closed, the pressure upon the hydraulic packing at the lower end of the 35 weight B' acts to force said weight and the oil-chamber upwardly, causing the oil or other liquid in the chamber to flow upwardly past the valve-closure d^{10} and through the aperture d^{12} in the stem and above the piston. 40 As the weight and oil-chamber move upwardly the weaker spring b^7 is first compressed by the pull on the flushing-valve, inasmuch as said flushing-valve remains 45 closed by the downward pressure of the water. When said spring is compressed, the pressure increases sufficiently to compress the stronger spring b^8 . The bottom of the oil-chamber is now in contact with the 50 weighted end of the lever e^2 , so that further upward movement actuates said lever, withdrawing the valve-closure E' from its seat in the lower end of the pipe E, instantly removing the pressure from the oil-chamber, owing 55 to the escape of fluid through the pipe E. This produces a sudden upward jump of the oil-chamber and through the joint action of the springs b^7 and b^8 jerks the flushing-valve from its seat, snapping the same upwardly 60 to a position shown in Fig. 4, or, in other words, against the lower end of the weight. The closing movement immediately begins. The gravity of the movable structure within the casing, including the oil-chamber and its 65 contents, causes the weight to gradually

slide downwardly, the rate of downward movement being determined by the rate of flow from above the piston into said chamber through the valve in the stem D and through the apertures in said pipe E. The flushing 70 operation cannot cease until the weight has descended sufficiently to bring the closure into positive contact upon the upper end of the sleeve b^{11} . The opening movement then at once begins. By the use of said sleeve b^{11} the wear upon the seat on the upper side of the base and also on the packing-washer b^{10} is avoided, and should the upper or seating end of the sleeve become slightly worn the packing-washer b^{13} may be moved to the other 80 side of the flange and said sleeve inverted, thus affording a new bearing-face. Owing to the groove in the base of said flange b^{12} , greater pressure is afforded above than below said flange, thus acting to hold the same 85 firmly seated when the flushing-valve is opened. As shown, an aperture positioned at F in the casing is provided at sufficient height above the base to prevent the escape of any fluid therefrom should any find its 90 way into the casing and also to afford access of air into the casing. For the purpose of draining out any fluid that might possibly find its way within the casing a passage g is provided in one side of the base, which extends downwardly therein and communicates with the passage g' , which opens into the flushing-pipe below the flushing-valve. Seated in said passage is a check-valve G, carried upon a screw-plug G' , which permits free 95 drainage into the flushing-pipe, but prevents 100 any backflow therefrom.

While I have shown but one construction embodying my invention, I do not purpose limiting this application otherwise than necessarily by the prior art, as obviously many details of construction and operation may be varied without departing from the principle of my invention.

I claim as my invention—

1. In an automatically-operating flushometer the combination with a valve of a fluid-receptacle movably supported above the same, a weight on said receptacle, a hydraulic packing on said weight of greater diameter than said valve, a stationary piston in said receptacle, a regulable passage therethrough, a trip-valve adapted to control the opening through the piston, means thereon adapted to contact with the bottom of said receptacle 115 to operate the trip-valve and resilient means 120 acting to unseat the valve when the trip-valve is open.

2. In an automatically-operating flushometer, the combination with a water-chamber, 125 of a valve adapted to close the outlet thereof, a movable fluid-receptacle above said valve, a piston therein adapted to elevate said movable receptacle, a sleeve connecting said piston with said receptacle, resilient means 130

therein connecting the piston and valve and an automatically-operated trip-valve in said receptacle adapted to snap the outlet-valve from its seat at the upward limit of movement of said receptacle.

3. In an automatically-operating flushometer, the combination with an outlet-valve adapted to close with the pressure, of a fluid-receptacle, yieldingly engaged therewith, a controlling fluid in said receptacle, a stationary piston in the receptacle, a regulable passage therethrough, a tube opening through the piston and a trip-valve controlling the same and adapted to be operated by the movement of said receptacle.

4. An automatically-operating flushometer comprising in combination with a supply-pipe and a flush-pipe, a valve seated to close the flush-pipe with the pressure and adapted to open automatically, a movable cup yieldingly engaged therewith, a fluid therein, a stationary piston in said cup, means permitting a graduated flow of fluid therethrough and a normally closed valve in said piston adapted to be operated by the movements of the cup.

5. In an automatically-operating flushometer, the combination with a casing of an inlet and an outlet pipe at the bottom thereof, a valve seated to close the outlet-pipe with the pressure, a sleeve extending upwardly therefrom concentric with the casing, a reciprocating cup above said sleeve, a weight carried thereon and extending into the sleeve, means thereon adapted to raise the cup by fluid-pressure, means yieldingly connecting the valve and cup and means in the cup acting to control the movement thereof.

6. In an automatically-operating flushometer the combination with a closed casing, of a chamber in the bottom thereof, an inlet and an outlet connected in said chamber, a cylindric sleeve extending upwardly through the top of the chamber into the casing, a reciprocating cup above said sleeve, means thereon fitting closely in said sleeve and adapted to operate the cup, a stationary piston extending into the cup, a controlling fluid in said cup, and a trip-valve in said piston adapted to be operated by the movement of the cup.

7. An automatically-operating flushometer comprising in combination, a closed casing, an inlet-pipe and a flushing-pipe, a valve seated to close the flushing-pipe, a vertically-extending sleeve concentric with the casing, a weight fitting closely therein and yieldingly connected with the valve and subjected to the upward pressure of the water from the supply-pipe and acting to open the valve thereby and valve-controlled means connected with said weight acting to regulate the descent of the same to close the valve.

8. An automatic flushometer comprising in combination an inlet-pipe and a flushing-pipe, a valve seated to close the flushing-pipe

with the pressure, a cylindric casing surrounding said valve and concentric therewith, a weight fitted within said casing, hydraulic packing carried at the lower end of the same and against which the upward pressure from the supply acts, a resilient connection between said weight and the valve adapted to permit upward movement of the weight independently of the valve, means acting near the limit of upward movement to unseat the valve, regulable means acting to control the rate of upward movement of said weight and regulable means acting to control the rate of downward movement of said weight in closing the valve.

9. In an automatically-operating flushometer, the combination with a casing and an inlet and a flush pipe connected therein near the bottom thereof, of a valve seated to close the flush-pipe with the pressure, a movable fluid-containing chamber above said valve adapted to be lifted by inlet-pressure, a spring affording the connection between said fluid-chamber and said valve permitting upward movement of the chamber independently of said valve and acting to lift the valve near its limit of upward movement, a piston fitted in said chamber, a regulating-valve therein adapted to control the flow of liquid in said chamber above the piston and the return flow therethrough and means for adjusting said regulating-valve.

10. In an automatic flushometer the combination with a casing having an inlet and a flush pipe connected therein, of a valve seating to close the flush-pipe with the pressure, a fluid-containing chamber in said casing adapted to be lifted by inlet-pressure, positive connection between said chamber and valve adapting said chamber to limited upward movement independently of said valve and to lift said valve near the limit of its upward movement, a fixed piston in the top of said chamber, a regulating-valve therein, means for adjusting said valve to control the rate of flow through the piston during the upward movement of said chamber, a release-valve in the piston normally closed during the upward movement of said chamber and adapted to be opened near the upward limit of such movement whereby the upward movement of the chamber is accelerated and the fluid above the piston flows back into the chamber as the cylinder descends.

11. In an automatic flushometer the combination with a casing of an inlet-pipe opening therewith, a flushing-pipe opening axially from the casing, a flushing-valve seated to close the same with the pressure, a fluid-containing chamber connected with the flushing-valve and positioned above the valve and adapted to be lifted by inlet-pressure and to unseat the flushing-valve near the upward limit of its movement, regulable means adapted to control the rate of upward movement

of said chamber and a release-valve adapted to control the rate of downward movement of said chamber in seating the valve.

12. In an automatic flushometer the combination with a casing of an inlet-pipe opening thereinto, a flushing-pipe opening axially therefrom, a valve seated to close said flushing-pipe with the pressure, a fluid-containing chamber in said casing adapted to be forced upwardly by inlet-pressure, springs affording a yielding connection between said chamber and the valve, a fixed piston in said chamber above which the fluid in said chamber is forced by upward movement of the chamber, means regulating the same and a release-

valve in said piston normally closed against upward pressure and adapted to be opened automatically near the upward limit of movement of the chamber affording quick release of the pressure in said chamber and permitting said chamber to fall by gravity to close the valve and means timing the discharge through said valve.

In testimony whereof I have hereunto subscribed my name in the presence of two subscribing witnesses.
